(57) **CLAIM**

An ornamental design for a wheel rim, as shown and described.

DESCRIPTION

FIG. 1 is a perspective view of the wheel rim, showing my new design;

FIG. 2 is a front view thereof; and,

FIG. 3 is a side view thereof.

The broken lines depict portions of the article that form no part of the claimed design.

1 Claim, 3 Drawing SheetsFIG. 1

FIG. 2

FIG. 3
